UNITED STATES PATENT OFFICE

JOSEPH BENNETT HILL, OF PHILADELPHIA, PENNSYLVANIA, ASSIGNOR TO THE
BARRETT COMPANY, A CORPORATION OF NEW JERSEY

PROCESS OF PRODUCING SULPHONIC ACIDS

No Drawing.

Application filed October 8, 1934. Serial No. 742,460.

My invention relates to the production of synthetic tanning materials and more especially to the production of sulphonic acid derivatives free from free sulphuric acid.

5 The common synthetic tanning materials are made as is well known by sulphonating aromatic hydrocarbons or their derivatives, such as phenol, naphthalene, anthracene, carbazole, etc., and either using these sul-
10 phonic acids so produced without further treatment for tanning purposes or condensing them with formaldehyde, sulphur-mono-
chloride or other condensing agents. In view
of the fact that the chemistry of the condensa-
15 tion reactions between the sulphonic acids and agents such as formaldehyde, sulphur monochloride and the like is not fully under-
stood, I intend that the term "condensing agent" as used throughout the specification
20 and claims shall include those materials which react in the presence of sulphonic acids to effect condensation of either the sulphonic acids themselves or of the sulphonic acids with the agents added to effect the condensa-
25 tion reaction. The sulphonation of the hydrocarbon as ordinarily effected cannot be readily carried to completion on account of the accompanying dilution of the sulphuric acid, and, therefore, gives a sulphonate product containing a considerable percentage of free sulphuric acid. The presence of this free sulphuric acid in the finished tanning material is considered harmful to the leather produced therefrom in that it tends
30 to produce rotting in the leather or ageing. This effect may be partly eliminated by partially neutralizing the sulphonate or its condensation product with soda, whereby the sulphuric acid being a somewhat stronger acid than the sulphonate, is more completely neutralized than the sulphonate. Even this treatment, however, is not wholly satisfactory and it is highly desirable to actually remove or eliminate free sulphuric acid
35 from the tanning material before it is used in the tanning process.

40 I have found that the well known procedure of effecting the sulphonation under reduced pressure, so as to vaporize out the water of reaction from the sulphonation mixture and
45 thereby prevent the dilution of sulphuric acid, is effective in producing a sulphonate acid comparatively free from sulphuric acid. By this means I have been consistently able to produce a sulphonate containing a maximum of .5% of sulphuric acid and containing generally much less than this figure. This sulphonate may either be applied to tanning operations directly or may be condensed with formaldehyde or other condensing
50 agents, in which case a condensed product is also produced comparatively free from sulphuric acid.

55 While the above procedure is readily applicable to the sulphonation of a large number of hydrocarbons without causing difficulty, there are cases, particularly where a low water insoluble content of the sulphonate acid is desired, to which the above process does not readily lend itself on account of the
60 fact, for example, that under certain conditions of temperature, concentration, etc., and where the sulphuric acid is exhausted or present in the sulphonation mixture in relatively small amount, side reactions take place giving
65 rise to the formation of insoluble compounds.

70 I have found that the difficulties may be overcome by a very simple expedient without materially affecting the quality of the product. In the sulphonation of naphthalene, for example, under reduced pressure, the formation of insoluble products does not appear to begin until the remaining free sulphuric acid gets down to the neighborhood of 5% of the sulphonation mix. The sulphonation can, therefore, be carried this far without endangering the quality of the finished product. I have found that this residual sulphuric acid can be readily consumed in sulphonating some lower boiling hydrocarbon, such as benzol or one of its homologues, which causes the absorption or elimination of the residual free sulphuric acid due to its interaction with these hydrocarbons to form the corresponding sulphonate acids at a lower temperature than that necessary when naphthalene alone is sulphonated. These low boiling hydrocarbons are preferably added in quantity in excess of that required to interact with the residual acid and this excess may be removed after
80

the completion of the sulphonation by distillation. The lower temperature used for this second sulphonation relative to that maintained in sulphonating the naphthalene 5 or similar compounds is not conducive to the formation of insoluble compounds, and this sulphonation can, therefore, be carried to completion and any excess of the more readily sulphonatable hydrocarbons distilled off 10 without inducing side reactions which cause the formation of such insoluble compounds. Such a process necessarily means that the finished product will contain a small percentage 15 of the sulphonic acid of the second hydrocarbon but, inasmuch as all of these sulphonic acids have been found to be more or less effective in tanning processes, this contamination is not seriously deleterious to the product, especially when it is used as an ingredient in 20 tanning compositions. One of the most satisfactory materials which I have found for effecting this secondary sulphonation is the fraction from coal tar naphtha boiling approximating between 150° C. and 200° C. and 25 consisting in large measure of the trimethylbenzenes which, like benzol, a compound hereinbefore referred to, are aromatic compounds, specifically of the benzene series.

30 While I do not wish to limit my invention to the sulphonation of naphthalene or to any exact process for effecting this sulphonation, the following will serve as an example of the manner in which my invention may be carried out.

35 One hundred and twenty pounds of refined naphthalene may be mixed with 100 pounds of 66° Bé. sulphuric acid and heated to 160° C. for a period of one hour. The sulphonator is put under a vacuum of about 22 inches of 40 mercury, below atmospheric pressure, and maintained at this pressure at a temperature of 155° C.-160° C. for about one hour additional. The vacuum is interrupted, the temperature reduced to 130° C. in any convenient 45 way and 35 pounds of the fraction from coal tar naphtha, boiling approximately between 150° C. and 200° C. are added to the sulphonator and the contents thoroughly agitated. Vacuum is again applied and the excess of 50 hydrocarbons distilled off. The product may be drawn off and used directly or may be condensed with formaldehyde in the usual manner to form the synthetic tanning material.

55 I claim:

55 1. The process which comprises incom-
60 pletely utilizing a quantity of sulphuric acid
added to an aromatic hydrocarbon for the
sulphonation thereof, adding a more readily
sulphonatable aromatic compound to the sul-
phonation mixture and causing the residual
sulphuric acid to be absorbed in the sulphonation
of said more readily sulphonatable com-
pound.

65 2. The process which comprises incompletely utilizing a quantity of sulphuric acid

added to naphthalene for the sulphonation thereof, adding a more readily sulphonatable compound of the benzene series to the sulphonation mixture; and causing the residual sulphuric acid to be absorbed in the sulphonation of said more readily sulphonatable compound.

3. The process which comprises incompletely utilizing a quantity of sulphuric acid added to an aromatic hydrocarbon for the sulphonation thereof, adding a more readily sulphonatable aromatic compound to the sulphonation mixture in excess of the quantity needed to combine with the residual sulphuric acid, causing the residual sulphuric acid to be absorbed in the sulphonation of said more readily sulphonatable compound and distilling off the excess of the more readily sulphonatable compound.

4. The process which comprises incompletely utilizing a quantity of sulphuric acid added to naphthalene for the sulphonation thereof, adding a more readily sulphonatable compound of the benzene series to the sulphonation mixture in excess of the quantity needed to combine with the residual sulphuric acid, causing the residual sulphuric acid to be absorbed in the sulphonation of said more readily sulphonatable compound and distilling off the excess of the more readily sulphonatable compound.

5. The process which comprises mixing with an aromatic hydrocarbon at least the theoretical quantity of sulphuric acid required for its sulphonation, sulphonating the hydrocarbon by causing it to interact with said acid under such conditions as to leave a small quantity of residual acid, then adding a more readily sulphonatable compound of the benzene series in quantity sufficient to interact with substantially all of said residual acid and causing said compound to be sulphonated by the residual sulphuric acid.

6. The process which comprises mixing with an aromatic hydrocarbon at least the theoretical quantity of sulphuric acid required for its sulphonation, sulphonating the hydrocarbon under reduced pressure under such conditions as to leave a small quantity of residual sulphuric acid, then adding a more readily sulphonatable aromatic compound in quantity sufficient to interact with substantially all of said residual acid and causing said compound to be sulphonated by the residual sulphuric acid.

7. The process which comprises mixing with an aromatic hydrocarbon at least the theoretical quantity of sulphuric acid required for its sulphonation, sulphonating the hydrocarbon under such conditions as to leave a small quantity of residual sulphuric acid, then adding an excess of a more readily sulphonatable compound of the benzene series, causing a portion thereof to be sulphonated by the residual sulphuric acid and distilling 130

off the excess of the more readily sulphonatable compound.

8. In the sulphonation of an aromatic hydrocarbon the step of eliminating residual sulphuric acid contained in the sulphonation mix which comprises causing it to react with a more readily sulphonatable hydrocarbon added thereto.

9. In the sulphonation of an aromatic hydrocarbon the steps which comprise eliminating residual sulphuric acid contained in the sulphonation mix by causing it to react with a more readily sulphonatable hydrocarbon added in excess thereto and removing the excess of the latter by distillation.

10. In a process of sulphonating naphthalene by reacting sulphuric acid therewith, the improvements which comprise sulphonating the naphthalene so as to leave at the completion of the sulphonation a quantity of residual acid in the sulphonation mixture equal to about 5% of the content thereof, then adding to said mixture a more readily sulphonatable compound of the benzene series and sulphonating said compound with the residual acid.

11. The process which comprises mixing with an aromatic hydrocarbon a quantity of sulphuric acid, sulphonating said hydrocarbon until the sulphonation mix contains about 5% free sulphuric acid, then adding an excess of coal tar naphtha boiling between 150° C. and 200° C.

12. The process which comprises mixing approximately 100 lbs. of 66° Baumé sulphuric acid with 120 lbs. of refined naphthalene, sulphonating said naphthalene until approximately 5% free sulphuric acid results, then adding an excess of coal tar naphtha boiling between approximately 150° and 200° C. and causing a portion thereof to be sulphonated by the residual sulphuric acid.

13. A tanning composition comprising a sulphonated aromatic compound in admixture with a small quantity of a sulphonated derivative of a more readily sulphonatable aromatic compound.

14. A product as in claim 13 combined with formaldehyde.

15. A tanning composition comprising sulphonated naphthalene in admixture with a small quantity of a sulphonated derivative of a more readily sulphonatable compound of the benzene series.

16. A product as in claim 15 combined with formaldehyde.

In testimony whereof I affix my signature.
JOSEPH BENNETT HILL.
